UNITED STATES PATENT OFFICE.

COLIN D. MAWER, OF NEW YORK, N. Y.

DESIGN FOR A BOTTLE.

No. 40,081.

Specification for Design.

Patented June 22, 1909.

Application filed March 10, 1909. Serial No. 482,624. Term of patent 7 years.

To all whom it may concern:

Be it known that I, COLIN D. MAWER, a citizen of the United States, residing in the city of New York, borough of Brooklyn, in the county of Kings and State of New York, have invented a new, original, and ornamental Design for a Bottle, of which the following is a specification, reference being had to the accompanying drawing, forming a part thereof.

I claim:

The ornamental design for a bottle, as shown.

COLIN D. MAWER.
